DEVICES FOR PLAYING TABLE FOOTBALL

Augustus Thomas Cave Insall, East Finchley,
London, and Frederic Eversden Andrews, East
Twickenham, England

Application December 7, 1932, Serial No. 646,198
In Great Britain January 4, 1932

2 Claims. (Cl. 273—94)

This invention relates to devices for playing indoor games like table football wherein a ball is propelled and moved about towards objectives by the manipulation of devices by the player or players. For convenience, the following description is confined to the use of the improved devices for playing table football, but it will be appreciated that the invention is equally applicable to analogous table games as for example table tennis, table golf, table hockey and so forth.

The object of the invention is to provide appliances of a non-complicated character, easy to operate for directing and projecting a ball over a playing area, and which, moreover, will invoke the skill and dexterity of the players in gaining their objectives, frustrating their opponent, and generally simulating the characteristics of the real game to which the invention is applied in miniature form.

The essential feature of the invention is the employment of a plurality of resiliently yieldable elongated members (e. g. strips of elastic rubber, helical springs, springily mounted rods or the like) spaced apart, preferably in parallel position, extending over the field of play, and lying thereon or slightly thereabove. By this arrangement a ball on the field of play may be propelled in various directions by flicking or plucking one or more of the said members. Great skill is required to select quickly the appropriate member to flick, or to anticipate the one towards which the ball is travelling, and to flick this one with requisite strength in the right direction.

An embodiment of the invention will be described in greater detail by way of example with the aid of the accompanying drawing, wherein:—

Figure 1 shows a plan view of an apparatus incorporating the invention, and used for table football; one end has been omitted for convenience, but it is in all respects similar to the end shown; and

Figure 2 is a sectional elevation taken on the line II—II of Figure 1.

Referring to the drawing a flat board 1 is provided on which appears marking representative of a football field. The actual field of play is enclosed by a net 2, whilst goals 3 are erected at each end, the net being attached to the uprights 4. The goals and the netting are preferably removable to facilitate packing.

There is a margin of the flat board 1 on each side of the field of play, and the margin may be formed with a slot 5 extending the full length of

the field of play or with other depressions, or the equivalent, to facilitate plucking the members 6.

Still referring to the example illustrated, across substantially the whole width of the base board 1, including the side margins, are stretched lengths of elastic rubber, helical springs or other similar elongated members 6 mounted in such a way that they are resiliently yieldable when flicked or plucked. The method of mounting or anchoring the ends is immaterial to the invention; for example, they may be knotted and fixed over notched edges on the exterior of the margins of the base. Or, as in the manner illustrated, the ends may be threaded through holes in the margins, then turned under, and secured by a thread, cord or wire, passed under and over through holes to form fastening stitches. In a further method they may be clipped to the board. The members 6 illustrated by way of example are strands of elastic rubber enclosed at their ends by reinforcing and protective rubber tubes 7. It will be observed that the protected ends 7 span across the aforesaid slots 5, the slot on each side in the form illustrated being common to all members 6. This renders it easy to flick or pluck the ends of the members 6 by the finger or with a suitable stick or other plectrum device.

The elastic strands or the like 6 pass under the nets 2 and lie on the field of play, or they may be spaced therefrom at any suitable height. Whilst the strands 6 are illustrated as lying transversely across the base and in parallel relation it is to be understood that they may be disposed at any other suitable position in relation to the field of play or to one another. For example, a pair of lengthwise bands or equivalents 9 are shown as lying along each side of the field of play.

It will now be readily appreciated by the foregoing, that a ball resting on the flat surface of any part of the field of play is always between two lengths of elastic rubber, springs or the like and that it can be moved backwards or forwards (or in any direction as will be described) by merely flicking the piece of elastic rubber, spring or the like which is stretched immediately behind it. This is done from the margins provided for the purpose, one player or team operating one margin (which propels the ball towards the opponents' goal) and the opposing player or team operating the other margin (which propels the ball in the opposite direction). Players on either side can operate the strands which extend over the margins on their respective sides.

- In constructing the members 6 it will be realized that many elastic materials would be suitable for the purpose set forth, like rubber strips or strands, coiled springs, piano wires, celluloid or whalebone strips, or any combination thereof. Further, the term resiliently yieldable elongated members used herein covers the foregoing or rigid rods of woods, metal or the like, mounted resiliently at their ends or otherwise. Referring to the drawing, by way of explanation and as one example, the strips 6 extending across the field of play may be regarded as rods of inherently non-yielding material, whilst the tubular protective ends hereinbefore referred to may be regarded as coil springs or other elastic connections between the rods and the margins of the base.
- The elastic rubber, springs or the like 6 may be stretched to any tension and apart from being disposed from side to side of the board, may be disposed in any other direction so that the ball may be shot in any desired direction on the board; thus "centring" as by the longitudinal strips 9, and shooting at goal from angles may be obtained.
- The elastic or the like may be any thickness or length and may be in the form of rubber bands or a single length of elastic or the like. They may be placed at any distance apart on the board according to the size of the ball used in the game.
- To introduce a variation into the form illustrated, any of the resilient members 6 may be stopped at one side of the field of play so as only to be operable from the other side. Further, any of the said members 6 may be stopped and fixed by one end actually in the field of play.

In a very simple form of carrying out the invention, the resiliently yieldable elongated members 6 are mounted between rigid side margins or edges or short pairs thereof not otherwise connected with one another, so that a table or other surface, preferably suitably covered (as by a baize cloth or the like) may be utilized as the field of play. In this case, the said margins would be provided with means for securing to the table or the like. The goals 3 and net 2 would be adapted for attachment to or support on the table in any convenient way.

It is preferred to construct the goals 3 with movable figures 10 representing goalkeepers. In the form illustrated these figures 10 are carried on horizontal bases 11 slidable transversely in the goal framework, and having an operating knob, handle or equivalent 12. Suitable means may be furnished in the interior of the goals to trap a ball which enters, and thus to prevent bouncing

out by rebound. For instance, a pair of taut wires 13 extending from side to side just off the goal "floor" would serve this purpose. The goal-keeper base 11 is preferably formed with inclined edges 14 to facilitate ejecting a trapped ball.

It will be observed from Figure 2 that the net 2 has a supporting string 15 spaced above the playing area at a distance less than the diameter of the ball 8. This provides that some shots may force the ball under the net 2, whilst others will project it over the top, and advantage is taken of these results to provide rules based on "corners" in the real game of association football.

We claim:—

1. A game device comprising a board to support a game piece and means for propelling the game piece comprising a plurality of elongated spaced apart members anchored at their ends to the board and extending over the top of the board, said members being elastic and tensioned for lateral flexure and subsequent release to strike and propel the game piece, the distance between adjacent members being greater than the width of the game piece, said members being disposed closely adjacent to the top surface of the board and the board being slotted adjacent to the anchored ends of the members to accommodate a member flexing implement, the area above the members being entirely unobstructed so that the game piece is free to move across the various members and also longitudinally relative thereto substantially from side to side of the board.

2. A game device comprising a board to support a game piece, and means for propelling the game piece comprising a plurality of elongated spaced apart members anchored at their ends to the board and extending over the top of the board, said members being elastic and tensioned for lateral flexure and subsequent release to strike and propel the game piece, the distance between adjacent members being greater than the width of the game piece, said members being disposed closely adjacent to the top surface of the board and the board being slotted adjacent to the anchored ends of the members to accommodate a member flexing implement, the area above the members being entirely unobstructed so that the game piece is free to move across the various members and also longitudinally relative thereto substantially from side to side of the board, and implement engageable protective reinforcing elements encasing the members at their ends.
